(57) **CLAIM**

The ornamental design for a video camera, as shown and described.

DESCRIPTION

FIG. 1 is a perspective view of a video camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a video camera showing my new design, wherein the strobe portion thereof is in the open position;

FIG. 9 is a front elevational view thereof; and,

FIG. 10 is a right side elevational view thereof, a left side elevational view of the strobe portion being a mirror image and being added to the main body of the video camera shown in FIG. 4.
